UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A T-PIECE FOR METALLIC CEILINGS.

SPECIFICATION forming part of Design No. 23,053, dated February 6, 1894.

Application filed January 8, 1894. Serial No. 496,199. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a T-Piece for Metallic Molding, of which the following is a specification, reference being had to the accompanying drawings, forming part hereof, which shows a T-piece for metallic molding designed according to my invention.

My design consists of a T-piece for metallic molding ornamented as follows: In general outline the T-piece is square. Along the edges there are ribs or ridges a , in which are arranged at equal distances apart concaved projections a' .

The flat portion B, of the T-piece, is raised above the edges and is connected with one of them by an inclined side-piece C, at the upper edge of which there is a roll or curved projection c . This inclined piece C, has a rib c' , dividing the piece C into two parts.

On the opposite side of the plate, in each corner there is a roll or curved projection D, which connects the flat portion of the T-piece with a downwardly-inclined portion D', which extends to the edge of the plate.

Arranged centrally in the flat T-shaped portion B, of the plate, is a rosette E, consisting of a concaved, central, circular projection e , and a series of radially-arranged pear-shaped projections e' , between which is arranged a series of ribs or bars e^2 , having cir-

cular knobs e^3 , at their outer ends. The rosette is surrounded by a rectangular series of pyramidal projections F. One side of the rectangular figure formed by the pyramidal projections is close to the edge of the roll c . From the other three sides projects a series of curved ribs G, which extend to the ribs at the edge of the plate. A central, curved rib g , within each set of ribs G, connects with a series of radial depressions g' . Triangular projections II, are arranged in the corners of the T-shaped, flat, raised portion B, and near the rolls or curved projections D, are bird-shaped projections I.

In each division of the portion C, there is a series of curved ribs c^2 , joining each other at their outer ends, and surrounding a triangular projection c^3 . Similar figures are formed on the parts D, D', of the plate.

The essential feature of my design is a T-piece for metallic molding, the raised body-portion being T-shaped and ornamented with a rosette surrounded by a square figure, from which radiate curved ribs, the inclined portions being ornamented with curved ribs.

I claim—

The design for a T-piece for metallic molding herein shown and described.

In testimony whereof I have hereunto subscribed my name.

WILLIAM S. GRAFTON.
